CLAIM

The ornamental design for a cooking appliance housing, as shown and described.

DESCRIPTION

FIG. 1 is a perspective view of a cooking appliance housing showing the new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a front view thereof, illustrating the location of various cross-sectional views;

FIG. 9 is a cross-sectional view thereof, taken along line 9-9 of FIG. 8;

FIG. 10 is an enlarged view of a portion of the cross-sectional view of FIG. 9;

FIG. 11 is a cross-sectional view thereof, taken along line 11-11 of FIG. 8;

FIG. 12 is an enlarged view of a portion of the cross-sectional view of FIG. 11;

FIG. 13 is a cross-sectional view thereof, taken along line 13-13 of FIG. 8; and,

FIG. 14 is an enlarged view of a portion of the cross-sectional view of FIG. 13.

The ornamental design of the cooking appliance housing includes the vertically-extending flutes shown in the figures. The broken lines are for environmental purposes only and do not form any part of the claimed design.
